UNITED STATES PATENT OFFICE

GEORGE A. WILLIAMS, OF SALT LAKE CITY, UTAH.

ASH-SEPARATOR.

No. 893,687.

Specification of Letters Patent.

Patented July 21, 1908.

Application filed November 6, 1907. Serial No. 400,929.

To all whom it may concern:

Be it known that I, GEORGE A. WILLIAMS, a citizen of the United States, residing at Salt Lake City, in the county of Salt Lake 5 and State of Utah, have invented certain new and useful Improvements in Ash-Separators, of which the following is a specification.

This invention relates to separators, and 10 more particularly to a machine for separating ashes and clinkers from coal.

An object of the invention is to provide a machine of this character for separating the ashes and clinkers from the unburned coal 15 which has been used chiefly in smelters, or other similar places where large quantities of coal containing ashes are thrown away.

Other objects and advantages will be apparent from the following description and it 20 will be understood that changes in the specific structure shown and described may be made within the scope of the claims without departing from the spirit of the invention.

In the drawings forming a portion of this 25 specification, and in which like numerals of reference indicate similar parts in the several views, Figure 1 is a side elevation of the machine, Fig. 2 is a top plan view, Fig. 3 is a section on the line 3—3 of Fig. 2, Fig. 4 is a 30 section on the line 4—4 of Fig. 2, Fig. 5 is a section on the line 5—5 of Fig. 2, Fig. 6 is a detail perspective view of one of the conveying buckets, Fig. 7 is a detail cross section on the line 7—7 of Fig. 1, Fig. 8 is a vertical longitudinal sectional view of a modified form of ash cylinder, Fig. 9 is a top plan view.

Referring now to the drawings, there is 40 shown a tank 10, which comprises the contracted front wall 11, the side walls 12 and 13 and a rear wall 14. The side wall 12 is provided with an opening 15 above the bottom of the tank, and web pieces 16 are secured to the front wall 12 and adjacent the opening 15, 45 for a purpose to hereinafter appear. The front wall 11 is provided with an opening 17, and secured to the front wall, there is shown an upwardly and incline wall 18, and the connecting web pieces 19.

50 A bracket 20 is secured at the upper end of the rear wall of the tank, and a second bracket 21 is secured to the rear wall 14, and this bracket extends rearwardly and upwardly, as shown. An elongated cylinder 22 has its ends disposed between the brackets

20 and 21 respectively, and this cylinder is preferably formed of foraminous sheet metal. The inner head 23 of the cylinder is cut away, as shown at 24, and a space is thus formed between the upper edge of this end of the cylinder and the inner side of the body of the cylinder. The upper end of the cylinder 22 is closed as shown at 25, and through this end and through the head 23, there is shown a longitudinally extending shaft 26, which 60 shaft has its ends journaled in the brackets 20 and 21.

The upper end of the shaft 26 is provided with a gear 27, and this gear is arranged to mesh with a similar gear 28, carried by a 70 horizontally and transversely extending shaft 29. The shaft 29 is journaled in brackets 30, which are secured to the bracket 21. One end of the shaft 29, carries a gear 31, and the opposite end of this shaft carries a band 75 pulley 32.

A hinge closure 33 is provided for the cylinder 22.

A clinker conveying belt 33' is shown as projecting partly into the tank 10, and the 80 lower portion of this belt is passed through the opening 17 in the tank and this belt is passed around a roller 34, which is journaled in the side walls 12 and 13 of the tank 10, and the upper portion of the belt 33 is 85 passed over the upper edge of the front wall 11, and this belt is extended forwardly and works over a roller 35, which is journaled in brackets 36, secured to the incline wall 18. The belt 33 is provided with buckets 36', and 90 these buckets are formed of foraminous material and are arranged to collect clinkers at the bottom of the tank 10.

A separating screen 37 is secured to the 95 side walls 12 and 13, for a purpose to be hereinafter described.

The tank 10 is adapted to contain water, the line of which is indicated at 34', and the screen 37 is thus disposed with a portion thereof within the water and a portion there- 100 of thereabove.

A coal conveying belt 38 is arranged transversely of the belt 33 and in rear of the screen 37, and this belt is passed over a roller 39 within the tank 10, and over a roller 105 40, outwardly of the tank, which roller is supported by brackets 40' mounted upon the wall 13 of the tank. Buckets 41 are secured to the belt 38 and these buckets are similar to the buckets 36, being somewhat 110

longer. The belt is thus arranged so that the buckets 41 carried thereby skim the surface of the water, and these buckets collect the unburned coal which floats upon the surface of the water.

The roller 40 carries gear wheels 42 at the ends thereof, and these gears are in mesh with similar gears 43 carried by the brackets 40.

10 The roller 35 carries a gear wheel 44, and this gear wheel is in mesh with a similar gear wheel 45, carried by a longitudinally extending shaft 46. The shaft 46 is journaled in brackets 47 which are secured to the wall 13 of the tank 10. The shaft 46 carries a gear wheel 48 between the ends thereof, and these gears mesh with the gears 43. The rear end of the shaft 46 is provided with a gear 49, and this gear meshes with the gear 81, on the shaft 29.

A coal and clinker chute 50 is disposed within the tank 10, and the lower end of the chute is disposed slightly above the bottom of the tank. The upper end of the chute 50 is disposed directly beneath the lower end of the cylinder 26, as shown.

An ash chute 51 is arranged beneath the cylinder 26, and this chute has a portion 52 extended along the entire distance of the cylinder, and a downwardly directed ash conveying portion 53 is secured to the portion 52, and this portion 53, extends to a suitable ash receiver, not shown.

In use, the ashes to be separated are placed within the cylinder 26 and the shaft 29 rotated by means of the pulley 32, which may be run by a suitable motor. This action of the shaft 26 will of course rotate the shaft 46, and in turn, this shaft will operate the belt 33. It will thus be seen, that as the cylinder 26 revolves, the ashes will be deposited into the conveying portion 53 of the chute 51, and the clinkers and unburned coal will be delivered from the cylinder 26 into the chute 50, whereby the clinkers and unburned coal will be deposited upon the bottom of the tank 10. The unburned coal, will of course float upon the surface of the water, and the coal will thus be collected 50 by the buckets 36 upon the belt 41. The clinkers, which remain upon the bottom of

the tank 10 will of course be collected by the belt 33.

The provision of the screen 37 is such that floating coal will be confined at one side of 55 the tank for collection by the belt 38.

In the modified form of ash cylinder shown in Figs. 8 and 9 of the drawings, the cylinder 22 has a portion of the foraminous material cut away as shown at 54, and this cut away 60 portion is thus arranged to lie directly above the chute 50. The ends of the cylinder are closed by heads 55 and 56, and projecting from the head 55 there is shown a trunnion 57, and this trunnion is journaled in a box 58 65 which is secured upon one side of the tank 10. The heads 55 and 56 are each provided with outwardly extending flanges 59, and these flanges are thus arranged for movement upon flanged rollers 60 which are carried by brackets 61 and 62. Each of the brackets 61 and 62 is provided with a runway 63 for the rollers 60. The bracket 62 is arranged outwardly of the tank, and this bracket is secured to the tank by means of 70 arms 64. The head 55 of the tank is provided with a bevel gear 65, and this gear is thus arranged to mesh with a pinion 66 which is carried at the end of a driven shaft 67. This shaft is supported in boxes 68 and 69 80 which are secured to the tank. The shaft is provided with a loose pulley 70 and a fixed pulley 71 by means of which the shaft may be ran from the drive shaft 29. The shaft 67 is also provided with a bevel gear 72 85 which may be engaged with a similar gear upon the roller 40.

What is claimed is:

In combination with a liquid-containing tank provided with a coal conveying belt 90 and a clinker conveying belt disposed at right angles to the first named belt, of a separating screen located within the tank and arranged to confine floating particles at one side of the tank for collection by the coal 95 conveying belt.

In testimony whereof I affix my signature, in presence of two witnesses,

G. A. WILLIAMS,
Witnesses:

J. FLETCHER, Jr.,
M. McPHETRES.
